UNITED STATES PATENT OFFICE.

EDWARD J. GULICK, OF JAMESTOWN, NEW YORK, ASSIGNOR TO THE FENTON METALLIC MANUFACTURING COMPANY, OF SAME PLACE.

HANDLE-BAR FASTENING FOR VELOCIPEDES.

SPECIFICATION forming part of Letters Patent No. 575,109, dated January 12, 1897.

Application filed September 30, 1895. Serial No. 564,169. (No model.)

To all whom it may concern:

Be it known that I, EDWARD J. GULICK, a citizen of the United States, residing at Jamestown, in the county of Chautauqua and State of New York, have invented certain new and useful Improvements in Handle-Bar Fastenings for Velocipedes, of which the following is a specification.

My invention relates to velocipedes, and has for its object to provide simple, cheap, and effective means whereby the handle-bar may be adjusted and fixed in different relative relations to the other parts of the machine, and whereby ready adjustment between the frame-head and fork-stem may be attained; and to these ends my invention consists in the various features of construction and arrangement of parts, substantially as hereinafter more particularly set forth.

Referring to the accompanying drawings, wherein I have illustrated the application of my invention to a bicycle-fork, Figure 1 is a perspective view of a portion of a handle-bar and stem. Fig. 2 is a perspective view of a portion of a fork-stem. Fig. 3 is a perspective view of the sleeve. Fig. 4 is a perspective view of the clamping-nut. Fig. 5 is a view showing the handle-bar and stem in side view and the other parts in section; and Fig. 6 is a side view, partially in section, of the handle-bar and stem, the fork, and a portion of the frame, showing the relations of the various parts.

It is well known that in the use of velocipedes it is often desirable to adjust the handle-bar in different positions, either by moving it up and down or turning it around, especially when the bar is reversible in its stem, in order to accommodate the handle-bar to persons of different heights and to various movements or positions in riding the machine, and numerous devices have been proposed for accomplishing this general result. It is also common to connect the frame-head with the fork-stem by means of ball-bearings, and it is also desirable to have means to adjust these connections and to take up for wear.

It is the object of my present invention to provide simple, cheap, and effective means whereby the handle-bar can be quickly and easily adjusted to the desired height or posi-

tion and securely clamped, either while the rider is on the machine or otherwise, and at the same time to provide means for compensating for wear between the fork-stem and frame-head connections, and more especially is it the object of my invention to provide a single means whereby both of these objects can be readily and quickly attained, and I will now proceed to describe the embodiment of my invention illustrated in the drawings.

The handle-bar A may be of any desired form or construction, and may be adjustable in its supports or not, as desired. In the present instance the T B is shown as having a cross-piece B', with serrations or notches b on one edge, while the handle-bar A is provided with an enlargement A', having corresponding notches a engaging the notches b on the cross-piece B', and there is a nut A², fitting the handle A and adjustable thereon to secure the handle-bar to the cross-piece B'. This cross-piece is rigidly connected to or formed with the stem B², and is adapted to be moved vertically and rotatively in the upper portion of the fork-stem C. In this way the handle-bar can be adjusted up and down or at any desirable angle, or turned in its socket in the manner substantially as indicated in Fig. 6, and can be secured in any desired position to suit the requirements or wishes of the rider.

The fork-stem (a portion only of which is shown in the drawings) is screw-threaded externally at c, and is split or formed into sections by the cuts or openings c', and is adapted to embrace the stem B² of the handle-bar and to be clamped thereon to secure the parts rigidly together.

Mounted on the fork-stem is a sleeve D, which in the present instance is provided with a downwardly-extending flange D', forming a recess D² for the reception of the ball-bearings D⁴, interposed between the sleeve and the steering-head F of the frame of the machine. This sleeve is provided with an internal screw-thread d, adapted to engage the screw-thread c on the fork-stem C, and the upper portion is split or formed into sections by the cuts or openings d'. The sleeve is also provided with external screw-threads d² for the reception of the nut E, and the upper portion of the sleeve is beveled, as at d³. The

sleeve is further preferably provided with an upwardly-projecting rim d^4 , forming a recess d^5 , into which fits the lower portion e^5 of the nut E.

- 5 The nut E, which may have any desired exterior configuration, is preferably provided with squared edges e , to receive a wrench, if necessary, or to aid in securing it in position. The interior of the nut E is screw-threaded, 10 as at e^2 , and adapted to engage the screw-threads d^2 on the sleeve D, and it is further formed with a recess to receive the balls e^3 , which are adapted to bear upon the beveled portion d^3 of the sleeve D. In order to prevent 15 the ball-bearings e^3 from falling out of the recess when the nut is removed, I provide the recess e^4 with an overhanging projection, shown in the present instance in the form of a wire e^6 , which can be readily sprung in 20 place, and which will retain the balls in the recess e^4 without interfering with their operation. Further, the nut has an inwardly-projecting flange e^7 , adapted to embrace the stem B² and prevent the entry of dirt, dust, &c. 25 The steering-head F of the frame is provided with an internal sleeve F', forming a bearing F² for the balls D⁴, in connection with the flange D' of the sleeve D. The steering-head is also provided at the point F³ with 30 ball-bearings F, interposed between the steering-head of the frame and the crown C² of the fork, and it is desirable to maintain these ball-bearings in proper relation and to adjust them for wear, and this I accomplish by means 35 of my sleeve and nut in the manner herein-after described.

With this construction of parts the sleeve D is screwed upon the split end C of the fork-stem, the screw-threads d meshing with the 40 screw-threads c thereon, and the nut E is secured upon the sleeve, its internal threads e^2 meshing with the external threads d^2 on the sleeve. The stem B² of the handle-bar is inserted in the split end of the fork-stem and 45 adjusted in the desired position, when, on turning the nut, the ball-bearings e^3 engage the beveled surface d^3 of the sleeve, forcing the split ends thereof inward, and in turn forcing the split ends of the fork-stem position 50 tively against the stem B², tightly clamping and holding the same in the position to which it is adjusted.

It will be seen that the ball-bearings engaging the beveled edge of the sleeve produce little or no friction, and at the same time force the split ends of the sleeve inward with great pressure, insuring an absolutely 55 secure adjustment of the stem of the handle-bar. Moreover, when the parts are in position the lower portion e^5 of the nut fits in the recess d^5 of the sleeve D, and the flange e^7

engages the stem B², forming practically dust-tight joints.

The above construction embodies a most effective fastening device for the handle-bar, and at the same time permits of its ready adjustment, as it is only necessary to turn the nut E slightly to relieve the pressure of the ball-bearings upon the beveled surface of the nut, when the handle-bar can be moved and adjusted as desired, and then by tightening the nut, which can be easily done, owing to the slight friction between the ball-bearings and the beveled portion of the sleeve, the parts can be securely clamped together. 75

When it is desired to adjust the sleeve with relation to the ball-bearings between it and the steering-head, the nut E can be loosened, when the sleeve can be turned on the fork-stem to adjust it in the desired position with relation to the steering-head and bearings between the same, and then the nut can be tightened again, and it will thus be seen that the same nut acts both to secure the handle-bar adjustably in the fork-stem, as well as to 85 secure and adjust the ball-bearings between the fork-stem and the steering-head of the frame.

What I claim is—

1. The combination with a contractile sleeve 90 provided with screw-threads and a smooth inclined bearing-surface, of a nut engaging the screw-threads of the sleeve, provided with a recess, and balls within the recess adapted to engage the bearing-surface of the sleeve to 95 contract the same, substantially as described.

2. The combination with the fork-stem, of a split sleeve mounted thereon having a beveled edge, a nut mounted on the sleeve, and ball-bearings interposed between the nut and 100 sleeve, substantially as described.

3. The combination with the fork-stem, of a split sleeve mounted thereon having a beveled portion, a nut fitting the sleeve having a recess containing ball-bearings, and means 105 for securing the bearings in the recess, substantially as described.

4. The combination with the split fork-stem and handle-stem fitting therein, of a split sleeve mounted on the fork-stem having internal and external screw-threads and a beveled edge, and a nut mounted on the sleeve having a recess, and balls engaging the faces of the recess and beveled portion of the sleeve, substantially as described. 115

In testimony whereof I have signed my name to this specification in the presence of two subscribing witnesses.

EDWARD J. GULICK.
